UNITED STATES PATENT OFFICE.

FRANK H. SLEEPER, OF WORCESTER, MASSACHUSETTS, ASSIGNOR TO SLEEPER & HARTLEY, INC., OF WORCESTER, MASSACHUSETTS, A CORPORATION OF MASSACHUSETTS.

COILING-MACHINE.

1,319,974.

Specification of Letters Patent. Patented Oct. 28, 1919.

Application filed August 18, 1917. Serial No. 187,020.

To all whom it may concern:

Be it known that I, FRANK H. SLEEPER, a citizen of the Dominion of Canada, residing at Worcester, in the county of Worcester and Commonwealth of Massachusetts, United States of America, have invented a new and useful Improvement in Coiling-Machines, of which the following, together with the accompanying drawings, is a specification.

The present invention relates to coiling machines, and more particularly to machines of this class which are adapted for the formation of spirally wound tubular coils of wire or other similar material, such as are used commonly as coverings for flexible shafting, electric cables and the like.

The invention resides in the provision of mechanism of this general class which is adapted for the formation of continuous tubular coil of more than one thickness of material, viz., an inner spirally wound coil and, as herein shown, an outer coil wound simultaneously upon the inner coil, with its convolutions interposed between adjacent convolutions of the inner coil. The invention resides in the combination and arrangement of parts, as hereinafter described and claimed, whereby the simultaneous winding and coiling of two continuous strips of material, constituting the inner and outer coils of the resulting flexible tube, is effected at a high rate of speed, with a continuous production of the tubing in its final finished form, the various mechanisms being so coördinated as to produce this highly desirable result. The various features of my invention are fully set forth in the following description and pointed out in the annexed claims, reference being had in this connection to the accompanying drawings, in which—

Figure 1 is a front view of a machine embodying my invention.

Fig. 2 is a rear view of the same showing the driving gears.

Fig. 3 is an enlarged sectional view, taken transversely near the front of the machine, and showing the mechanism for coiling the material which constitutes the inner wall of the tube.

Fig. 4 is a view, partly in section, of a sample of tubing which constitutes the product of my machine.

Fig. 5 is a plan view, partly in section, near the front of the machine, and showing

the simultaneous coiling operations of the material constituting both the inner and the outer walls of the tubing.

Fig. 6 is a front view, partly in section, of the mechanism for coiling the material which constitutes the outer wall of the tube.

Fig. 7 is a fragmentary sectional view illustrating the guiding devices for the material of said outer wall.

Fig. 8 is a fragmentary sectional view illustrating the grinding and coiling devices for the material constituting the outer wall, in the act of being wound upon the inner wall of the tubing.

Like reference characters refer to like parts in the different figures.

The mechanism constituting my invention is carried on a framework or base 1, which affords spaced front and rear walls 2 and 3 for the support of the shafting as hereinafter described. The mechanism is driven from a main driving shaft 4, Figs. 1 and 2, which carries on its rear end fast and loose pulleys of ordinary construction, as indicated by the broken lines 5, Fig. 2. The driving belt, operated from a suitable source of power not shown, is employed to drive the shaft 4 at the will of the operator, and when said belt is running idly on the loose pulley, the shaft 4 may be rotated by the operator by a hand wheel 6, Fig. 1, as when introducing the material into the coiling mechanism, to inaugurate the coiling operation, as hereinafter described.

The shaft 4 carries a pinion 7 which meshes with a gear 8 on a shaft 9. The shaft 9 carries a pinion 10 which meshes with gears 11 and 12 on shafts 13 and 14 respectively, and the latter gears are respectively in mesh with gears 15 and 16 of shafts 17 and 18, so that the pairs of adjacent shafts 13, 17 and 14, 18 are driven in unison from a single source at substantially the same speeds.

The pair of shafts 13 and 17 at the front of the machine carry coöperating feed rollers 19, 19 rotating in opposite directions, and the pair of shafts 14 and 18 carry similar feed rollers 20, 20. These rollers 19 and 20 are suitably grooved, as shown at 21, 21, Fig. 3, to receive and advance by their rotation in unison the continuous strip of material 22, which is subsequently coiled in spiral form to constitute the inner wall of the flexible tubing. If desired, in each machine, sets of rollers 19 and 20 may be pro-

vided in different sizes, and with different size grooves 21 to accommodate material of different diameters, said rollers being interchangeable on their several shafts 13, 17 and 5 14, 18. Furthermore, the front end bearings of upper shafts 17 and 18 may be adjusted vertically, within suitable limits, by means of hand screws 23, 23, Fig. 1, in order to vary the pressure of the feed rolls 19 10 and 20 on the material fed thereby. To this end, the teeth of the intermeshing pairs of gears 11, 15 and 12, 16 are made loose enough to allow for such angular movement of shafts 17 and 18, and the rear end 15 bearings of said shafts are swiveled or pivoted on horizontal axes at right angles to the axes of said shafts, in a manner well known in mechanism of this class, but not herein shown nor specifically described, 20 since the same forms no part of the present invention.

The continuous strip of material 22 in its passage between the coöperating pairs of feed rolls 19 and 20 is suitably guided by a 25 channel formed between a pair of plates 24, 24, and in advance of the rolls 20, in a similar channel 25, Fig. 3, formed between a pair of plates 26, 26. The channel 25 delivers the material to a coiling mechanism, 30 which consists of three grooved rollers 27, 28 and 29, arranged substantially as shown in Fig. 3, on three sides of the space into which the material 22 is thus fed. The roller 27 is journaled in the forked end of 35 a bar 30 which is held stationary to the wall 2 by means of bolts 31. As thus held, the groove of roller 27 is disposed below the material 22 as it emerges from channel 25, and the inclination of this roller and 40 groove is such as to deflect the material slightly laterally of the line of feed into the groove of roller 28, which is offset slightly from the initial line of feed of the material through channel 25. The roller 28 45 is journaled in the forked end of a bar 32 which is slidably supported on a bracket 33, and has elongated slots 34 therein for the reception of bolts 35, 35 projecting outwardly from wall 2. The roller 28 is thus 50 horizontally adjustable toward and away from the fixed roller 27, in order to regulate the diameter of the coil into which the material 22 is to be formed, and said roller 28 is firmly held in any predetermined position of horizontal adjustment by means of clamping plate 36, Fig. 5, and nuts 37, 37 which are drawn tight on the bolts 35.

The third grooved roller 29 is journaled in the forked end of a bar 38 which is pivoted on a stud 39 projecting from wall 2. The groove of this roller is slightly offset forwardly from the groove of roller 28, whose inclination is such as to guide the material into the groove of roller 29 and thus impart 55 the proper direction to the material to form

a spiral coil. The roller 29 is adjustable vertically by means of a bolt 40 passing through the outer end of bar 38 and bearing against bar 32, as shown in Fig. 3, said bolt being retained in any predetermined position of adjustment by means of a nut 41. The roller 29 is thus raised and lowered in accordance with the diameter desired for the coil which is formed by the coöperation of the three rollers 27, 28 and 29. 75

In forming such a coil, the coiling operation is started by winding the end of the material around a mandrel for a few turns or convolutions, and then inserting said turns in position between the coiling rollers 80 27, 28 and 29, which are then adjusted to the proper position to give a tubular coil of the required diameter. As a means for making these initial turns or convolutions by hand, particularly when the material 22 85 is so heavy as to resist easy flexure, the frame of the machine provides a suitable socket 42 for the insertion of a mandrel 43, which latter is adapted to be turned by a detachable crank 44. This mandrel is in 90 substantial alinement with the channel 25 through which the material is fed to the coiling mechanism, and upon removal of the interposed roller 28 and bar 32, the material may be advanced to the mandrel by 95 feed rollers 19 and 20, operated by hand wheel 6. The end of the continuous strip of material is then bent over into engagement with a shoulder 45 of the mandrel and a few turns or convolutions are then wound on 100 the mandrel by the rotation of the crank 44. Thereupon, the coils or turns are removed from the mandrel and the feed rolls 19 and 20 are reversed to bring this coiled end between the coiling rollers 27 and 29. 105 Thereupon, the roller 28 is returned to its operative position, and together with the roller 29 adjusted for the commencement of the coiling operation.

In front of the plates 26 the wall 2 supports coöperating guide members 46, 46 for the strip of material 47 which constitutes the outer wall of the spirally wound tubular coil. As herein shown, this material is substantially triangular in cross-section, 110 with a narrow portion thereof adapted to enter spaces between adjacent convolutions or turns of coiled inner wall, and with a wide or flattened portion opposite said narrow portion in the extreme outer surface of the coil. Obviously, however, the cross sectional shape of this strip of material 47 is immaterial, since my invention contemplates the formation of both outer and inner walls of the tube from material 115 of any desired cross sectional shape. The substantially triangular shape herein shown is merely to illustrate one way of carrying the invention into practice and, in accordance therewith, the guide members 46 pre- 120 125 130 135

vide the groove shaped to correspond to said material, as shown in Figs. 6 and 7. These members 46 are provided in a plurality of interchangeable sets to accommodate material of different cross-sectional shapes, as will be obvious from an understanding of my invention. The guide members 46 lead and direct the material 47 into close proximity to the coil of inner wall 10 material 22, whose formation has been started, and then stopped to permit the end of strip 47 to be twisted a couple of times around the same, prior to the operation thereon of its coiling mechanism, as hereinafter described.

The shaft 14 carries a gear 48 which operates through an idler gear 49 to drive a shaft 50 in the same direction as shaft 14, said shaft 50 having a gear 51 in mesh with the idler gear 49. The shaft 50 in turning drives an upper shaft 52 through gears 53 and 54 in mesh with an idler 55. The forward ends of shafts 50 and 52 carry coiling disks 56 and 57, which thus rotate 25 in the same direction, with their peripheries adjacent the spirally wound tubing which is moved outwardly between said peripheries by the action of coiling rollers 27, 28 and 29. These disks operate to press the material 47 firmly into the spaces between adjacent convolutions of the coil formed from material 22, the lower disk 56 moving in the same direction as the material 47 on the under side of said coil, and the upper disk 57 moving in the same direction as the material on the upper side of said coil. The action of the disks in guiding and pressing the material into spiral form on the rotating coil is supplemented by the end of stationary clamping plate 36 which prevents deflection of the material 47 in a horizontal direction. The shafts 50 and 52 are adapted to receive disks 56 and 57 of varying diameter in accordance with the 45 diameter of the tubing to be formed and in accordance with the character of the outer wall material 47. In addition, the forward end of shaft 52 has its bearing 58 vertically adjustable in the wall 2, as shown 50 in Fig. 3, the rear end of said shaft having its bearing swiveled the same as shafts 17 and 18. The hand-screw 59, or other equivalent means, is employed to retain the bearing in suitable position for the operation of the disk 57, the lower end of said bearing being supported by a compression spring 60 which is acted against by hand screw 59.

The operation of the machine will be 60 clear from the foregoing description. It is apparent that the machine as above described is adapted for the manufacture of the double thickness spiral tubing at a high

rate of production, and in the simplest and most economical manner. The entire absence of a mandrel and plurally grooved forming rolls in the coiling mechanism for the inner winding allows said coiling mechanism to be operated at an extremely high speed, since the material which forms said inner winding is progressively and rapidly guided by simple grooved rolls into an easy bend. In my machine the material for the inner winding does not have to pass into a restricted or tortuous space between a mandrel and plurally grooved forming rolls, wherein it is apt to jam, as in other machines turning out a similar product. Hence, there is practically no limitation on the speed at which the winding mechanism 80 may run. Furthermore, the winding of the outer wall is a comparatively simple matter, since the material constituting said outer wall naturally follows the spiral direction of the spaces between adjacent convolutions 85 of the inner wall, the coil which constitutes said inner wall acting by its rotation as a mandrel for drawing the material 47 thereon.

I claim,

1. In a machine of the class described, means for feeding the wire to be coiled, coiling means, means for feeding a second wire in a line tangential to the coil formed by said coiling means, a pair of pressure 95 rolls one above and one below the coil for confining said second wire, and an abutting wall bearing against the coil on the side opposite the line of feeding.

2. In a machine of the class described, 100 means for feeding a wire to be coiled, means for coiling the wire, means for feeding a second wire in a line tangential to a coil formed by said coiling means, a pair of pressure rolls, one above and one below the 105 coil, for operation on said second wire, said rolls having their axes approximately in the vertical plane of the axis of the coil, and pressure resisting means bearing against the coil on the side opposite the 110 feeding mechanism.

3. In a machine of the class described, means for feeding a wire to be coiled, means for coiling the wire, means for feeding a second wire in a line tangential to a coil 115 formed by said coiling means, and a pair of pressure rolls, one vertically above and the other vertically below the axis of the coil, and means for positively rotating said rolls in the same direction.

Dated this 10th day of August 1917.

FRANK H. SLEEPER.
